UNITED STATES PATENT OFFICE

165,685

CIGARETTE DISPENSER

Robert Hunt, Saginaw, Mich.

Application July 20, 1951, Serial No. 15,968

Term of patent 14 years

(Cl. D85—2)

To all whom it may concern:

Be it known that I, Robert Hunt, a citizen of the United States, residing at Saginaw, in the county of Saginaw and State of Michigan, have invented a new, original, and ornamental Design for a Cigarette Dispenser, of which the following is a specification, reference being had to the accompanying drawing, forming part thereof.

I claim:

The ornamental design for a cigarette dispenser, as shown.

ROBERT HUNT.
